CLAIM

The ornamental design for a dual receptacle carrier, as shown and described.

DESCRIPTION

FIG. 1 is a front perspective view of a dual receptacle carrier showing our new design;

FIG. 2 is a top plan view thereof;

FIG. 3 is a front elevation view thereof;

FIG. 4 is a right side elevation view thereof;

FIG. 5 is a rear elevation view thereof;

FIG. 6 is a left side elevation view thereof; and,

FIG. 7 is a bottom plan view thereof.

The broken lines in FIGS. 1-7 depict unclaimed portions of the dual receptacle carrier and form no part of the claimed design.

1 Claim, 5 Drawing Sheets(56)
